UNITED STATES PATENT OFFICE.

LOUIS PAGEAU, OF MONTREAL, QUEBEC, CANADA.

BOOT OR SHOE.

1,327,772.

Specification of Letters Patent. Patented Jan. 13, 1920.

Application filed January 16, 1919. Serial No. 271,398.

To all whom it may concern:

Be it known that I, LOUIS PAGEAU, a British subject, residing at 237 St. Zotique street, in the city of Montreal, Province of Quebec, Dominion of Canada, have invented certain new and useful Improvements in Boots or Shoes; and I do hereby declare that the following is a full, clear, and exact description of the same.

10 The present invention relates to improvements in ventilated boots or shoes, and the main object is to construct a boot of the type indicated in such a way that its cost will not be increased, as well as to provide 15 a perfect ventilation of the boot.

A further object is to provide a boot of this character in which the ventilation means will be simple, and the boot cheap to manufacture.

20 The invention consists of a cored or recessed heel provided with a plurality of ventilating openings, the heel portion of the sole being provided with one or more holes communicating with said recessed heel.

25 Referring to the drawings:

Figure 1 is a side elevation of a boot to which the invention is applied.

Fig. 2 is a view of a portion of the sole of the boot and heel.

30 Fig. 3 is a top view of the boot illustrating the heel portion of the sole.

Fig. 4 is a fragmental, longitudinal section taken centrally of the heel and sole.

Like numerals of reference indicate corresponding parts in each figure.

In the drawings 1 represents a boot having the sole 2 and heel 3. The heel is provided with a central, longitudinal recess 4; and 5 are lateral slots communicating at their inner ends with said recess 4. The 40 heel portion of the sole is provided with a single, elongated opening 6 communicating with the recess 4 at one end and projecting forwardly beyond the heel 3 at 7. The opening 6 is preferably covered with a 45 netting 8 of any suitable material so that a proper ventilation may be obtained, but the netting must be fine enough to prevent any dirt or dust from entering the boot.

What I claim as my invention is: 50

A ventilated boot or shoe comprising a heel formed with a central, longitudinal recess which opens through its upper face, and with a plurality of lateral slots or holes communicating at their inner ends with said recess, a sole formed with a single, longitudinal opening which extends forwardly beyond the heel and the rear portion of which registers with the recess in said heel, and a strip of netting entirely covering the sole 60 opening; substantially as described. 55

Signed at Montreal, Quebec, Canada, this 7th day of June, 1918.

LOUIS X PAGEAU.
